ATTORNEYS

UNITED STATES PATENT OFFICE.

CHARLES S. PRICE, OF BETHLEHEM, PENNSYLVANIA.

DESIGN FOR A RADIATOR CAP.

Application filed May 20, 1924. Serial No. 9,662. Term of patent 3½ years.

To all whom it may concern:

Be it known that I, CHARLES S. PRICE, a citizen of the United States, residing at Bethlehem, in the county of Northampton and State of Pennsylvania, have invented a new, original, and ornamental Design for Radiator Caps, of which the following is a specification, reference being had to the accompanying drawing, forming part thereof.

Figure 1 is a plan view of my ornamental design for a radiator cap.

Figure 2 is a front elevation thereof.

Figure 3 is an end elevation thereof.

I claim:

The ornamental design for a radiator cap, as shown.

Apr. 14, 1924.

CHARLES S. PRICE.
